(57) **CLAIM**

The ornamental design for a star shaped driver, as shown and described.

DESCRIPTION

FIG. 1 is a back upper perspective view of a star shaped driver.

FIG. 2 is a front view of the star shaped driver of FIG. 1. FIG. 3 is a back view of the star shaped driver of FIG. 1. FIG. 4 is a left side view of the star shaped driver of FIG. 1.

FIG. 5 is a right side view of the star shaped driver of FIG. 1.

FIG. 6 is an enlarged top view of the star shaped driver of FIG. 1; and,

FIG. 7 is an enlarged bottom view of the star shaped driver of FIG. 1.

The broken lines shown in FIGS. 1, 2, 3, 4, and 5 depict a slope change. None of the broken lines form a part of the claimed design.

1 Claim, 7 Drawing Sheets
